VENEER WALL CONSTRUCTION

Charles S. Finzer and Edward G. Finzer, Sugarcreek, Ohio, assignors to The Finzer Brothers Clay Company, Sugarcreek, Ohio, a corporation of Ohio

Application October 12, 1934, Serial No. 748,052

13 Claims. (Cl. 72—19)

The invention relates generally to the application of a veneer to walls, and more particularly to means and methods for economically and advantageously applying relatively thin blocks, tiles, or bricks and the like, to building walls as a veneer covering therefor; and this application is a continuation of common subject matter in our pending application Serial No. 725,720, filed May 15, 1934, entitled Veneer wall construction.

10 Certain prior veneer wall constructions have provided metal plates or sheets adapted to accommodate a large number of the bricks or veneering units, and having spaced projections for securing the bricks in position.

15 With these constructions, a very large quantity of material is required, and great difficulty is had in fitting the plates to corners and offsets, and around windows and the like; because in order for the plates to secure the veneering units in proper arrangement as to courses and whole and half or fractional units, accurate and skillful cutting or overlapping of the plates is required.

20 Other prior constructions have provided individual clips or horizontally disposed strips for securing the bricks or veneering units in position, but this necessitates locating the clips one by one or the strips in spaced relation vertically on the wall, so as to secure the bricks in horizontal courses, and requires excessive time and trouble.

25 Moreover, where the wall surface is irregular, as for instance in the case of lapped or cove siding, the individual clips or horizontally disposed strips cannot be used satisfactorily, because the projections for securing the bricks in place would be located in different vertical planes on the same wall.

30 Many of these prior constructions require that the projections be bent in such a way as to tend to cause breaking or chipping of adjacent edges of the bricks, in order to hold the bricks in position.

35 Accordingly, it is an object of the present invention to provide improved means for securing veneer bricks or veneering units to a wall and the like, which means requires a relatively small amount of material and is easily attached to the wall.

40 Another object is to provide improved veneer brick securing means which can be attached in position to a whole section of wall before the bricks are applied.

45 A further object is to provide means for at-

taching the improved brick securing means to the wall, the attaching means being adapted to anchor the mortar between the bricks to the wall when the bricks are cemented in position.

5 Another object is to provide improved veneer brick securing means which can be used equally well upon walls having smooth or irregular surfaces such as are provided by lapped or cove siding.

A further object is to provide improved veneer 10 brick securing means which does not require the locating of clips or projections in vertical spaced relation for each horizontal course of bricks.

15 Another object is to provide improved veneer brick securing means which is easily fitted to 15 corners, offsets, windows and the like, and which provides for horizontal adjustment of the bricks therein; in order to readily accommodate and secure all of the bricks throughout a wall in proper arrangement.

20 A still further object is to provide improved veneer brick securing means to which each brick is easily applied and then individually clamped and interlocked without danger of chipping or 25 breaking adjacent edges of the bricks.

25 And finally, it is an object of the present invention to incorporate all of the foregoing advantageous features in a simple and economical construction which is easily applied to the wall, and which provides the same flexibility in 30 constructing a veneer wall as is present in the laying up of a brick wall by a mason.

35 These and other objects are attained by the improvements comprising the present invention, which may be stated in general terms as including strips adapted for attachment to a wall in horizontally spaced relation, each strip having a series of projections thereon arranged to secure a plurality of vertically spaced veneering units, the units having grooved opposite side surfaces 40 into which the projections are adapted to be pressed for clamping and interlocking the units in position, and preferably double headed attaching means for attaching the strips to the wall and extending outwardly between adjacent units 45 for anchoring mortar therebetween.

46 Referring to the drawings forming part hereof,

Figure 1 is a fragmentary perspective view of a 50 corner of a wall having a veneer applied thereto in accordance with the present invention, parts of the veneer being removed and broken away to show the construction of one form of the improved veneer securing means.

55 Fig. 2 is a sectional view as on line 2—2, Fig. 1,

showing the method of clamping the improved securing means to the veneer bricks;

Fig. 3 is a detached perspective view of one of the veneer bricks used in connection with the improved securing means;

Fig. 4 is a fragmentary sectional view showing a modified form of securing strip secured to a wall and clamping a veneer brick thereon;

Fig. 5 is a fragmentary side elevation of another modified form of the improved securing strip;

Fig. 6 is a detached perspective view of a preferred form of the improved securing strip especially adapted for use with lapped or cove siding or the like;

Fig. 7 is a similar view of another preferred form adapted for the same purpose;

Fig. 8 is a sectional view showing the application of the strip of Fig. 7 to lapped siding;

Fig. 9 is a sectional view showing the application of the strip of Fig. 6 to double cove siding;

Fig. 10 is a fragmentary sectional view taken on line 10—10, Fig. 8;

Fig. 11 is a fragmentary sectional view taken on line 11—11, Fig. 9;

Fig. 12 is a sectional view of a modification of the strip of Fig. 6 applied to a wall coated with plastic material; and

Fig. 13 is a sectional view of a modification of the strip of Fig. 7 applied to a wall coated with plastic material.

Similar numerals refer to similar parts throughout the drawings.

In Fig. 1 is shown a portion of the corner of a building wall, including the intersecting walls 6 and 7, which may be of wood, and as shown in Fig. 2, may be constructed of tongue and groove siding. The walls 6 and 7 are secured to studding 8, to which are secured lath 9 covered with plaster 10 forming the inside building walls, all in a usual manner. Preferably, the outer surface of the walls 6 and 7 are first covered with a heavy paper covering indicated at 11 for insulation purposes.

The veneer wall shown in the drawings and described herein is formed of veneer bricks, but other veneering units can be substituted therefor, without departing from the scope of the invention as defined in the appended claims.

The improved veneer brick securing means may include the strips 12, preferably of galvanized sheet steel, and these strips are placed upon the walls in vertically extending rows as shown in Fig. 1 the rows being preferably horizontally spaced apart a distance less than the length of one of the veneer bricks to be applied.

The strips 12 are provided with longitudinally spaced projections 13, which may be stamped or punched out of the strip and are bent outwardly therefrom substantially at right angles. The gauge of the strips is such that the projections 13 are substantially rigid and yet have sufficient ductility that they may be bent by means of a special tool in a manner to be hereinafter described.

The projections 13 are preferably formed flat and are vertically spaced in such manner that a veneer brick 14 will fit between each pair of projections, and so that the bricks after being fitted in the projections will be spaced vertically so as to allow for horizontal mortar joints, as indicated at 15.

At the bottom of the wall, relatively short securing strips 12' are provided for being aligned and preferably abutted with the strips 12. These bottom strips 12' are preferably of substantially

non-corrosive material such as copper, for the purpose of better resisting the tendency to rust prevalent at the lower portion of the wall. An outwardly projecting substantially rigid securing flange 16 may be provided at the bottom of each of strips 12' for the purpose of securing the underside of the first course of bricks, and substantially rigid projections 13' similar to projections 13, are provided for securing and interlocking the top faces of the first course of bricks 10 and the bottom faces of the next course above.

In applying the improved veneer wall construction to a wall, the improved securing strips 12 and 12' are first attached to the wall in vertical rows horizontally spaced apart less than the 15 length of a brick, preferably by means of double headed nails 17 which are driven through nail holes in the strips into the wall, the nail holes being preferably located one at the side of each two adjacent projections. The double 20 headed nails 17 may be staggered, that is, placed one at one side of two adjacent projections and then one at the other side of the next two adjacent projections, and so on, so as to securely attach each strip to the wall throughout the 25 length of the strip.

After a relatively large section of the wall surface has had the securing strips attached thereto in this manner, the veneer bricks 14 are applied. These bricks are adapted to be inserted 30 one between each pair of projections 13, as best indicated in dot-dash lines in Fig. 2. The bricks 14 may be inserted in a direction perpendicular to the wall, and may be slid horizontally in the projections in order to vary the vertical mortar 35 joints 18 therebetween so as to accommodate the bricks to offsets, windows or other irregularities in the wall. As shown in Fig. 1, the horizontal spacing of the improved strips 12 and 12' is easily 40 adjusted to fit a corner or irregularity in the wall, and corner bricks 14' may be provided for fitting around the corner of the wall.

Preferably, the bricks 14 and the corner bricks 14' are provided on their upper and lower surfaces with longitudinal grooves indicated at 19, and the 45 projections 13 and 13' are made just long enough to slightly overlap or extend over the grooves when the bricks are in place. After a number of the bricks have been inserted in between the substantially rigid projections 13, 13' and 16, the 50 projections may be bent or pressed into the grooves adjacent thereto as shown in Figs. 1 and 2, in order to clampingly engage the grooves and rigidly interlock the bricks in position, the projections being pliable enough to be bent but not 55 resilient. A special tool may be provided for this purpose, such as the pliers indicated at 20 in Fig. 2. The upper and lower jaws 21 of the pliers are adapted to simultaneously press a projection at the upper surface and a projection at 60 the lower surface of each brick, so as to clamp and securely interlock the brick in place without any danger of chipping or breaking edges of the brick.

As indicated, the double headed nails 17 are 65 located between adjacent projection 13 or 13' and to one side thereof so as to permit insertion of the jaws of the pliers 20.

After the bricks have been clamped by the projections in the above manner, the mortar joints 70 may be filled in to give the wall a finished appearance and to cement the bricks in place. The double headed nails 17 project into the mortar joints between the bricks and provide a means of anchoring the mortar to the wall.

The improved strips require a relatively small amount of material and are easily applied. Moreover, no accurate measuring is required for locating the strips on the wall, because the projections are already properly spaced for securing the veneer bricks in horizontal courses.

Due to the fact that the horizontal spacing of the strips may be varied slightly to fit adjacent to corners and irregularities in the wall, and that the bricks 14 may be moved horizontally after being inserted in the projections 13 to fit the bricks to corners, windows and the like; the present improved veneer wall provides the same flexibility during construction as is present during the laying up of an ordinary brick wall by a mason.

The modified form of improved strip indicated at 112 in Fig. 4 is channel-shaped in cross section, and may have veneer securing projections 113 and side flanges 122. The strip 112 is preferably attached to the wall 107 by means of double headed nails 117 passing through the flanges 122 and the wall covering 111 into the wall.

The channel shape of strips 112 provides for spacing the veneer bricks 114 from the wall 107, which may have a continuous or unbroken surface, so as to provide an air space therebetween, where the same is desired for insulation purposes.

The modified form of improved strip indicated at 212 in Fig. 5 has the veneer securing projections 213 extending forwardly from the front surface of the strip, and is provided between pairs of projections 213 with angular tangs or projections 225 extending rearwardly. The tangs 225 are preferably oppositely disposed to the strip at acute angles.

The strips 212 are adapted to be used where it is desired to apply veneer over walls which are first coated with cement, grout or other plastic material. The strips are applied to the wall when the grout is in plastic condition, and the angular tangs provide means for securely anchoring the strips thereto after the grout has set.

The modified forms of improved strip indicated at 12a and 12b in Figs. 6 to 11 inclusive, are particularly adapted for use on walls having continuous or unbroken, but uneven surfaces, such as provided by lapped or cove siding. As shown in Fig. 6, the strip 12a is channel-shaped in cross section having the web 30a and inturned flanges 31a. As shown in Fig. 7 the strip 12b is channel-shaped in cross section having the web 30b and outturned flanges 31b.

Projections 13a are stamped or punched in the web 30a and bent outwardly therefrom substantially at right angles in the same manner as the projections 13 in strips 12. The projections 13a are longitudinally spaced so that a veneer brick 14 will fit against the web 30a between each pair of projections, and so that the bricks after being fitted in the projections will be spaced vertically to allow for horizontal mortar joints.

Similarly, projections 13b are stamped or punched in the web 30b and bent outwardly therefrom substantially at right angles. The projections 13b are longitudinally spaced so that a veneer brick 14 will fit between each pair of projections. However since the flanges 31b are outturned, the bricks 14 will fit against the outer edges thereof. This requires increasing the length of the projections 13b so that they project beyond the plane of the outer edges of flanges 31b

a distance equal to the distance flanges 31a project beyond web 30a.

The projections 13a and 13b are pliable or bendable but not resilient, so that they may be bent into engagement with the grooves of veneering units to rigidly interlock the same, in the same manner as the projections 13 in the form shown in Figs. 1 and 2.

The form of strip 12b facilitates manufacturing since the flanges 31b and projections 13b extend in the same direction from the web 30b and may be formed in the same operation. Also the strip 12b has an additional advantage in that the bricks do not abut the web 30b and therefore inaccuracies at the base of the projections 13b do not cause undue distortion of the projections when the bricks are forced therebetween.

The improved strips 12a and 12b are provided with nail holes 32 located at intervals in the webs 30a and 30b, respectively. Some of the nail holes 20 may be located one midway between each pair of adjacent projections, and others may be located one midway between pairs of adjacent projections, as best shown in Figs. 6 and 7. Thus, when the strips are applied to lapped siding, 33, as 25 shown in Fig. 8, or to double cove siding 34, as shown in Fig. 9, ordinary nails 35 can be driven through any of the holes 32, depending upon which holes come over spaces between the laps 30 or over coves.

In this way, the strips 12a and 12b may be applied without bending them inwardly by hammering over spaces or coves in the surface of the siding, by selecting the nail holes at points where the strips substantially abut the siding, as shown 35 in Figs. 8 and 9. Such bending would prevent the projections from securing the veneering units in proper location.

If desired, double headed nails may be used between adjacent projections, as shown in Fig. 2. 40

The projections 13a and 13b are located on strips 12a and 12b, respectively, with respect to the ends thereof, so that the adjacent ends of the strips may be spaced apart on the wall a sufficient distance to allow for expansion, as indicated at 45 36 in Fig. 9.

The channel form of the strip 12a or 12b strengthens the same so as to prevent accidental bending thereof during handling or installation. Moreover, the flanges 31a and 31b of the strips 50 provide for spacing the veneering units from the wall, as shown in Figs. 10 and 11 for insulation purposes.

Furthermore, the channel forms provide a strong rigid bridge over the spaces or coves in the 55 siding, so as to form a more rigid support for the veneering units, than is provided by flat strips.

The strip 112a shown in Fig. 12, is channel-shaped in cross section similar to the strip 12a, and has side flanges 131a, but is provided between 60 pairs of adjacent projections 113a with rearwardly extending tangs 125a, preferably oppositely disposed to the strip at acute angles.

The strip 112b shown in Fig. 13, is channel-shaped in cross section similar to the strip 12b, 65 and has side flanges 131b, but is provided between pairs of adjacent projections 113b with rearwardly extending tangs 125b, preferably oppositely disposed to the strip at acute angles.

The strips 112a and 112b are adapted to be used 70 for applying veneer to walls which are first coated with cement or other plastic material, the tangs being inserted in the plastic material 140 when soft, so that when the plastic material hardens the strips will be anchored therein.

The term wall as used herein, is intended to include side walls of building, top walls or ceilings or roofs and bottom walls or floors.

We claim:—

5 1. In veneer wall construction, a wall, spaced strips on the wall, means attaching the strips to the wall, each strip having longitudinally spaced pliable projections for securing adjacent veneering units, and a plurality of veneering 10 units each having grooved opposite surfaces, the projections being rigidly engaged with the grooves for interlocking the veneering units in position on the wall.

15 2. In veneer wall construction, a wall, laterally spaced strips on the wall each having longitudinally spaced pliable projections, means attaching the strips to the wall, and a plurality of veneering units each having opposite surfaces provided with grooves and fitting between a pair 20 of said projections, said projections being rigidly interlocked with said grooves.

25 3. In veneer wall construction, a wall, laterally spaced strips on the wall each having longitudinally spaced pliable projections for securing adjacent veneering units, a plurality of veneering units each having opposite surfaces provided with grooves, and the projections being rigidly interlocked with said grooves.

30 4. In veneer wall construction, a wall, laterally spaced strips on the wall each having longitudinally spaced pliable projections for securing veneering units, a plurality of veneering units each having opposite surfaces provided with grooves and adapted to fit between a pair of said 35 projections, and each pair of projections being adapted to be simultaneously tool pressed into rigid interlocking engagement with the opposite surface grooves of a veneering unit.

40 5. In combination with a veneering unit having opposite surfaces provided with grooves, a strip having a pair of spaced pliable projections, the veneering unit being adapted to fit between said projections, and the projections being adapted to be simultaneously tool pressed into rigid engagement with the opposite surface grooves of the veneering unit for interlocking the unit to the strip.

45 6. The method of applying veneering units and the like to a wall, which includes attaching strips having longitudinally spaced pairs of pliable projections to the wall in laterally spaced relation, inserting veneering units having grooved opposite surfaces each between a pair of projections, and then simultaneously bending opposite projections into rigid interlocking engagement with the grooves adjacent thereto of a unit.

50 7. In veneer wall construction, an unbroken wall, a strip on the wall having a pair of longi-

tudinally spaced projections securing a veneering unit therebetween, and means attaching the strip to the wall, the strip being channel-shaped in cross section for spacing the veneering unit from the wall to provide an insulation space therebetween. 5

8. Veneer wall construction including a wall, spaced strips on the wall having spaced pliable projections rigidly securing the veneering units, the strips being channel-shaped in cross section for spacing the veneering units from the wall and having side flanges at their open sides, and means attaching the side flanges to the wall. 10

9. In veneer wall construction, a strip adapted for attachment to a wall, said strip having spaced forwardly extending pliable projections for rigidly securing veneering units, and said strip being provided with rearwardly extending oppositely angled projections for being imbedded in the wall. 15

10. In veneer wall construction, a strip adapted for attachment to a wall, said strip being channel-shaped in cross section and having a web and rearwardly extending flanges, spaced pliable projections for rigidly securing veneering units 20 extending forwardly from the web, and oppositely angled projections extending rearwardly from the web for being imbedded in the wall.

11. In veneer wall construction, a wall, a strip on the wall, the strip being channel-shaped in cross section and having a web and flanges angular thereto, longitudinally spaced pliable projections extending forwardly from the web substantially at right angles to the web and to the flanges for rigidly securing veneering units therebetween, and means attaching the strip to the wall. 25 30 35

12. In veneer wall construction, a wall, a strip on the wall, the strip being channel-shaped in cross section and having a web and rearwardly 40 extending flanges angular thereto, longitudinally spaced pliable projections extending forwardly from the web substantially at right angles to the web and to the flanges for rigidly securing veneering units therebetween, and means attaching the strip to the wall. 45

13. In veneer wall construction, a wall, a strip on the wall, the strip being channel-shaped in cross section and having a web and forwardly 50 extending flanges angular thereto, longitudinally spaced pliable projections extending forwardly from the web substantially at right angles to the web and to the flanges for rigidly securing veneering units therebetween, and means attaching the strip to the wall. 55

CHARLES S. FINZER.
EDWARD G. FINZER.
